UNITED STATES PATENT OFFICE.

LAURA M. COOLIDGE, OF CHICAGO, ILLINOIS, ASSIGNOR TO BUNTE BROTHERS, OF CHICAGO, ILLINOIS, A CORPORATION OF ILLINOIS.

DESIGN FOR A CANDY-CONTAINER.

50,554.

Specification for Design.

Patented Apr. 3, 1917.

Application filed January 2, 1917. Serial No. 140,330. Term of patent 14 years.

To all whom it may concern:

Be it known that I, LAURA M. COOLIDGE, a citizen of the United States, residing at Chicago, in the county of Cook and State of Illinois, have invented a new, original, and ornamental Design for a Candy-Container, of which the following is a specification, reference being had to the accompanying drawing, forming a part thereof.

The figure is a perspective view of a candy container illustrating my new design.

I claim:

The ornamental design for a candy container as shown.

LAURA M. COOLIDGE.
